BOILER FOR USE IN OIL FIRING

Vincent L. Falotico, Far Rockaway, N. Y.

Application October 20, 1933, Serial No. 695,797

1 Claim. (Cl. 122—225)

The object of my invention is to provide a boiler which will result in efficient and economical operation with oil firing.

These objects, and other advantageous ends
5 which will be described hereinafter, I attain in
the following manner, reference being had to
the accompanying drawing in which—

Fig. 1 is a side elevation of a sectional boiler constructed in accordance with my invention.

10 Fig. 2 is a transverse sectional elevation taken on the line 2—2 of Fig. 1.

Fig. 3 is a longitudinal sectional elevation taken on the line 3—3 of Fig. 2.

15 Each of the water sections 5-11, inclusive, is provided with a lower baffle 19, and each of the sections 6-12, inclusive, is provided with an upper baffle 20. In the assembled boiler as shown in Figure 3, the lower baffles 19 form a horizontal baffle wall 21 extending from the front of the boiler to a point a short distance from the back of the boiler, and the baffles 20 form a baffle wall between the baffle wall 21 and the top of the boiler extending from the rear of the boiler to a point a short distance from the front of the boiler. Hence, the combustion gases rising from the combustion chamber 16 pass rearward under the baffle wall 21, around the free end of the latter and then forward between the baffle walls 21 and 22, and finally rearward again between the top of the boiler and the baffle wall 22, thence out through the flue. As a result, a maximum absorption of heat in all of the water-carrying parts of the boiler during passage of the hot combustion gases, is obtained.

35 Referring to Figures 1, 2, 3.—4 represents a steam or hot water heating boiler which includes a plurality of sections 5, 6, 7, 8, 9, 10, 11, 12. The sections are adapted to contain water, and their bottoms are connected by nipples 13 where-
40 by the interior of all the sections are in communication and water can flow from one section to the other through the passageways provided by said nipples. Nipples 14 provide communication between the upper spaces of the sections.
45 The steam or hot water is distributed by outlets

15. Sections 5, 6, 7, and 8 extend to floor and provide for forming combustion chamber 16, thus surrounding the front, rear, sides and bottom of combustion chamber 16 with water. Sections 9, 10, 11, 12 are similar to sections 5, 6, 7, 8 in design, except they do not extend to floor, but instead extend to and are supported by base 18, thus forming a travel for the gases of combustion and also providing additional heat absorbing surfaces 17.

The common type of oil burning boiler has the base extending from the front section to the rear section. A combustion chamber is provided by lining the front, sides, and to a distance of the required length and depth, the base and portion of the heating surfaces with fire brick or other fire protecting material. The result is that since there is no water around the combustion chamber, the high temperature therein results in a high radiation loss through the base. Further, all heat absorbing surfaces back of, and below the top of rear wall of combustion chamber becomes useless in its function of absorbing heat, in that the gases of combustion will fail to come in contact with these surfaces. Further, in common types of boilers it is practically impossible to prevent infiltration of air between the base and floor, and also between the base and sections. 10 15

The object of my invention is to overcome the above described faults. Referring to Figs. 2 and 3.—16 is the combustion chamber, formed by sections 5, 6, 7, and 8, and is lined with fire brick or other fire protecting material. The heat of combustion absorbed by the fire brick or other lining protecting sides and floor of combustion chamber, will be absorbed by the water surrounding the combustion chamber. Since this water is in communication with the other water in the boiler it will result in increased efficiency and also result in reduction of radiation losses around the combustion chamber. Further, the gases of combustion in traveling through the boiler to the chimney will of necessity have to come in contact with surface 17, which I have provided as additional heat absorbing surface. Further, by my assembly of sections as shown in Figs. 1 and 3, the only air to enter the boiler will be that blown in by oil burner blower, thus eliminating all infiltration losses. To provide for conditions whereby the length of combustion chamber 16 varies it is proposed to add additional sections 6 and 7, such that the combination of sections 5 to 8 inclusive will give required length to 16.

Having thus described my invention, what I claim as new and desire to secure by Letters Patent is:—

An oil fired boiler comprising a plurality of hollow water sections substantially rectangular in outline, each of said sections being provided with nipples to connect the water compartment of each section with the water compartment of the adjacent sections, the forward sections extending from the top of the boiler to the floor, 55

the rearward sections extending from the top of the boiler to a level above the floor, each of said sections with the exception of the rearmost having a hollow water-carrying baffle located at a distance from the top of the boiler, said water-carrying baffles being horizontally aligned to form a baffle wall extending from the front of the boiler to a point near the back of the boiler, each of said sections with the exception of the forwardmost having a hollow water-carrying

baffle located between said first-named baffle and the top of the boiler, said last-named baffles being horizontally aligned to form a baffle wall extending from the rear of the boiler to a point near the front of the boiler, the boiler flue being located at the rear of the gas compartment formed between the top of the boiler and said last-named baffle wall.
